(57) CLAIM

The ornamental design for a golf club head, as shown and described.

DESCRIPTION

FIG. 1 is a front perspective view of the golf club head as claimed herein;

FIG. 2 is a heel plan view of the golf club head thereof;

FIG. 3 is a bottom plan view thereof;

FIG. 4 is a top plan view thereof; and,

FIG. 5 is a toe plan view thereof.

The broken line showing is for illustrative purposes only and forms no part of the claimed design.
